UNITED STATES PATENT OFFICE

95,539

DESIGN FOR A SHOE

Henry W. Nieman, Columbus, Ohio

Application March 1, 1935, Serial No. 55,684

Term of patent 3½ years

To all whom it may concern:

Be it known that I, Henry W. Nieman, a citizen of the United States, residing at Columbus, in the county of Franklin and State of Ohio, have invented a new, original, and ornamental Design for a Shoe, of which the following is a specification, reference being had to the accompanying drawing, forming a part thereof.

Fig. 1 is a perspective view of the shoe showing my new design;

Fig. 2 is a top plan view thereof.

I claim:

The ornamental design for a shoe as shown.

HENRY W. NIEMAN.
